UNITED STATES PATENT OFFICE.

JOHN PATERSON RAMAGE, OF LIBERTON, SCOTLAND.

ENVELOP-MAKING MACHINE.

1,393,162.

Specification of Letters Patent. Patented Oct. 11, 1921.

Application filed July 21, 1920. Serial No. 398,035.

To all whom it may concern:

Be it known that I, JOHN PATERSON RAMAGE, a subject of the King of the United Kingdom of Great Britain and Ireland, and 5 resident of Kirkby Mount, Alnwickhill Road, Liberton, Midlothian, Scotland, envelop maker have invented certain new and useful Improvements in Envelop-Making Machines, of which the following is a specification.

- 10 This invention relates to machines for the manufacture of envelopes having a transparent window to give visibility to the address on the inclosed correspondence and the object of the present invention is to provide 15 improved mechanism for applying the transparencies or transparent blanks to the envelop blank prior to the folding of the latter, the improved mechanism expediting and facilitating the manufacture of the envelopes 20 and also reducing the distance as compared with known machines over which the envelop blank must be transported from the gumming operation to the final application and adhesion of the transparency.
- 25 According to the present invention, the envelop blank, with the usual aperture therein, is gummed around the aperture, and is transferred by a conveyer to an elevating table adapted to raise the gummed blank 30 to a plane above the conveyer, the application of the transparency to the envelop thus taking place at a higher level than the conveyer.

The application of the transparency to the 35 envelopes is effected by the action of a self-adjusting pressure block upon the transparencies contained within a suitable magazine and said pressure block is arranged to descend upon the pile of window blanks 40 and exert pressure thereon while the elevating table holds the gummed envelop blank in contact with the lowermost transparency, the pressure block exerting pressure on the transparencies by its own weight and being 45 so fitted as to be lifted out of contact with the transparencies before the elevating table descends.

In order that the invention may be more 50 clearly understood, reference is hereinafter made to the accompanying drawings showing the preferred construction of the machine.

Figure 1 is a side view of the machine.
Fig. 2 is a plan view to a larger scale.

Fig. 3 is a vertical sectional view through 55 the magazine and elevating table.

In the construction illustrated, the envelop blanks 1, in which the usual window aperture has already been cut, are laid in a pile face downward upon a table 2, the 60 apertures being immediately beneath the vertically reciprocated gumming die, 3, which may be of the usual construction adapted to apply gum around the window aperture and to lift the topmost envelop 65 blank 1 from the pile and deposit it upon a horizontally reciprocating conveyer or carriage.

The conveyer preferably comprises two parallel bars 4 having projections 5 for engaging the edge of the envelop blank so as to transport the latter into a position over the elevating table 6 with the gummed window aperture immediately beneath the magazine 7 containing the window trans- 75 parencies 8.

The magazine 7 is fitted with a plurality of vertically movable spring catches or buffers adapted to support the edges of the lower transparencies, said catches preferably 80 comprising spring controlled vertical rods 9 terminating at their lower ends in circular flanges or buffers 10. The magazine also carried a plurality of vertically movable keeper rods 11 which are adapted to descend 85 upon and hold the envelop blank in position upon the elevating table 6 as the latter rises.

When the elevating table 6 has brought the envelop blank into contact with the lowermost transparency, the table 6 raises the 90 buffers 10 and the pressure block 12 comes into operation, causing the lowermost transparency to adhere firmly to the envelop.

The pressure block 12 is preferably carried at the lower end of a spindle 13 working through a ball or roller friction clutch 14 having coned surfaces 15 and 16 which support balls or rollers arranged to bear on the spindle 13, so that raising of the coned surface 15 releases the spindle 13. The 100 coned surface is carried by a sleeve having a collar 17 adapted to be lifted by a yoke 18 projecting from a vertical rod 19, the clutch 14 being carried by a boss 20 at one end of a bracket 21 sliding on the rod 19 and fixed upon a vertical shaft 22. It will be understood that by movement of the rod 19 and shaft 22 relatively to each other, the

clutch 14 will engage or disengage the spindle 13 and the pressure block 12 may be lifted or lowered by raising or lowering the clutch 14.

5 Preferably the clutch 14 is raised and lowered to raise and lower the pressure block 12 by reciprocating the vertical shaft 22 and rod 19, the clutch 14 being released to allow the pressure block 12 to rest on the transparencies by lifting the rod 19 relatively to the shaft 22 when required, but it will be understood that the rod 19 could be fixed and the yoke 18 movable thereon or the rod 19 could move with the clutch 14 and the 10 yoke 18 be operated independently.

In the construction illustrated, the pressure block 12 is normally supported clear of the transparencies and caused to descend by lowering the rod 19, shaft 22 and clutch 20 14 until the block 12 is in close proximity to the transparencies whereupon the rod 19 is arrested in its downward motion so as to release the clutch 14 and allow the pressure block 12 to descend by its own weight and 25 exert pressure on the transparencies, while the elevating table 6 holds the envelop in close contact with the lowermost transparency. Before the elevating table 6 commences to descend, the pressure block 12 is 30 lifted clear of the transparencies by raising the shaft 22 and clutch 14.

The magazine 7 is preferably fitted with side plate springs 23 (shown dotted in Fig. 1) for exerting lateral pressure on the transparencies, the side springs being bent outwardly at their lower ends, so as not to exert pressure on the lower portion of the pile of transparencies. In this manner the weight of the pile of transparencies is taken 40 off the lowermost transparency, so that when the newly applied transparency is being withdrawn from the buffers 10, there is never more weight upon it than the head of transparencies beneath the side springs 23.

45 During the application of the transparency to the envelop, the conveyer rods 4 return to position beneath the next gummed envelop lifted by the gumming die 3 and at 50 the same time, a second conveyer or carriage 24 mounted at a higher level than the conveyer rods 4, moves into position beneath the raised elevating table 6.

The second conveyer 24 preferably forms 55 a rearward extension of the conveyer rods 4, being mounted on brackets 25 so as to move therewith. As the elevating table 6 descends, the keeper rods 11 descend therewith and thus assist the newly applied transparency to detach itself from the buffers 10. Thereupon the keeper rods 11 release the envelop on the table 6 and enable the latter to deposit the envelop upon the second conveyer 24, having projections 60 65 adapted to engage the edge of the envelop

and deliver it either over a folding box or to suitable folding mechanism. At the same time, the conveyer rods 4 will have brought another gummed envelop blank over the elevating table 6.

70 When the conveyer 24 is to deliver the envelop to a folding box, the envelop may be engaged by fingers or projections adapted to be limited in their forward travel by motion relatively to the conveyer 24, such motion being absorbed by springs so that said springs expand during the initial return motion of the conveyer 24 and thus cause the fingers or projections to dwell and retain the envelop temporarily beneath the magazine. This arrangement obviates a period of dwell between the forward and return motion of the conveyer 24 and also reduces the length of travel of the envelop from beneath the magazine to the folding 75 80 box, thereby increasing the speed of operation of the machine.

85 On the drawings I have shown the second conveyer 24 as delivering the envelops on to endless traveling cords 27 from whence the envelop may be delivered to folding mechanism, but it will of course be understood that my invention may be readily adapted to combined gumming and folding machines in which case the conveyer 24 90 95 would deliver the envelop blank to the folding box.

100 It will be understood that suitable mechanism must be provided for synchronous reciprocation of the gumming die, conveyers, elevating table, pressure block and keeper rods and that only such parts of the mechanism as are necessary for the present invention to be clearly understood, have been described herein.

105 The conveyers may be made adjustable to accommodate envelop blanks of different sizes, for which purpose the rods 4 may be mounted on transversely adjustable cross-heads or guides.

110 When the present improvements are applied to machines for gumming the window aperture only (that is to say, in which the flaps of the envelop blank have already been gummed the application of the transparency 115 to the envelop at a level above the conveyer rods 4, enables the distance between the gumming die 3 and elevating table 6 to be reduced to such an extent that the envelop on the table 6 may overlap the envelop on the conveyer rods 4 without interfering with the gumming operation and window application taking place either simultaneously or in quick succession.

120 Claims:

125 1. A machine for applying transparencies to envelop blanks comprising a feed table, a picker, a reciprocated feed conveyer adapted to receive the blanks from said picker, an elevating table to which said 130

- blanks are transported by said conveyer, a fixed magazine for the transparencies above said table, means for retaining the transparencies in the magazine a self-adjusting clutch-controlled pressure block adapted to descend upon the transparencies, and a conveyer on a plane above said feed conveyer.
2. A machine as specified in claim 1 in which the transparency retaining means comprise vertically movable spring-controlled rods terminating at their lower ends in circular flanges and side spring plates adapted to exert lateral pressure on the transparencies.
3. A machine for applying transparencies to envelop blanks comprising a fixed magazine, a vertically movable table beneath said magazine, a pressure block adapted to descend upon the transparencies in the magazine, a spindle supporting said block, a clutch adapted to permit said spindle to lift, means for raising or lowering said clutch and mechanism for releasing said clutch.
4. A machine as specified in claim 1 in which the distance between the feed table and magazine is shortened to such an extent that a part of one envelop may overlap the succeeding envelop.
5. A machine as specified in claim 1 provided with a plurality of vertically movable keeper rods adapted to hold the envelop blank upon the elevating table as the latter rises and means for reciprocating said rods.
6. A machine as specified in claim 1 in which the delivery conveyer forms an extension of the feed conveyer and is adapted to move therewith.

JOHN PATERSON RAMAGE.
